(No Model.)

H. WIDDOWS.
TIRE TIGHTENER.

No. 447,390.

Patented Mar. 3, 1891.

By his

Inventor
Henry Widdows,
Attorney,

J. R. Littell,

UNITED STATES PATENT OFFICE.

HENRY WIDDOWS, OF NEWMAN, ILLINOIS.

TIRE-TIGHTENER.

SPECIFICATION forming part of Letters Patent No. 447,390, dated March 3, 1891.

Application filed June 20, 1890. Serial No. 356,055. (No model.)

To all whom it may concern:

Be it known that I, HENRY WIDDOWS, a citizen of the United States, residing at Newman, in the county of Douglas and State of Illinois, have invented certain new and useful Improvements in Tire-Tighteners; and I do hereby declare that the following is a full, clear, and exact description of the invention, which will enable others skilled in the art to 10 which it appertains to make and use the same.

This invention relates to tire-tighteners; and it has for its object to provide a device of this character which will serve the twofold purpose of tightening the tire and retaining the latter in place.

15 A further object of the invention is to provide a simple and improved tire-tightener which will possess advantages in point of inexpensiveness, ease of operation, durability, and general efficiency.

In the drawings, Figure 1 is a perspective view of a vehicle-wheel having my improved tire-tightener applied thereto. Fig. 2 is a detail longitudinal sectional view of the same.

25 Fig. 3 is a detail transverse sectional view. Fig. 4 is a detail perspective view of the parts comprised in the invention detached. Fig. 5 is a perspective view of the tightening device.

30 Corresponding parts in the figures are denoted by the same letters of reference.

Referring to the drawings, A designates a wheel provided with my improved tire-tightener B, disposed between the opposing ends 35 of two or more sections of the felly a. The tightener B comprises two corresponding caps mounted upon the opposing ends of two sections of the felly, a portion of one or both said sections being cut away to form an intervening

40 space between the caps. The latter consist of approximately U-shaped plates C, embracing the ends of the felly-sections, and are provided with outward extensions c, projecting beyond the felly and at each side of 45 the tire to retain the latter upon the felly.

C' designates face-plates disposed over the end faces of the felly-sections and secured to or formed integral with the plates C. The opposing plates C' are respectively provided 50 with right and left hand screw-threaded perforations c' c'.

D designates the tightening-screw formed

with a central enlarged portion d, from each side of which projects an arm D', provided, respectively, with right and left hand screw-threads adapted to engage the correspondingly-threaded plates C' and project within perforations a', provided in the felly. The portion d is provided with transverse holes or perforations d' d' at right angles to each other and adapted to receive an adjusting-rod for tightening the screw.

For filling the space formed between the tire and the portion d of the tightening-screw and preventing an accumulation of earth or other substance therein, I provide a block E. The latter has its inner face formed concave, adapting it to fit over the periphery of the portion d, while its outer face is slightly convex to conform to the periphery of the felly.

To further insure the tire against displacement from the felly, approximately U-shaped plates F are provided, embracing the felly at points thereon and projecting beyond the same at each side the tire, said plates being 75 secured to the felly by screws or rivets f.

The operation and advantages of my invention will be readily understood by those skilled in the art to which it appertains. To effect the tightening of the tire, the perforations d' in the screw are engaged by a suitable rod or bar and the said screw turned in a direction to throw the opposing ends of the felly-sections farther apart, thereby enlarging the periphery of the wheel and binding the same against the tire. The plates C, projecting at each side the latter, serve to retain it against displacement from the felly, while by the employment of the block E the advantages of a continuous felly are retained.

I claim as my invention—

1. In a tire-tightener, the combination, with the tightening-screw disposed between the opposing ends of two felly-sections and comprising right and left hand threaded extensions and the central cylindrical portion, of a filling-block provided with a concave inner face corresponding to the periphery of said circular portion and adapted to be disposed between the latter and the tire, substantially as and for the purpose set forth.

2. In a vehicle-wheel, the combination, with a tire-tightener comprising opposing caps mounted upon the opposing ends of the two

5 felly-sections and provided, respectively, with right and left hand screw-threaded perforations, said caps being extended over the said edges of the tire, and a tightening-screw provided with right and left hand screw-threaded extensions engaging the correspondingly-threaded perforations in the cap, and with a central cylindrical portion, of a filling-block provided with a concave inner face and a
10 diametrically-convexed outer face, said block conforming to the contour of said circular portion and the tire and adapted to be disposed between the same, substantially as and for the purpose set forth.
15 3. In a tire-tightener, the combination, with

the opposing caps provided, respectively, with right and left hand threaded perforations, of a right and left hand threaded tightening-screw engaging the corresponding perforations and provided with an enlarged 20 central portion, and a filling-block adapted to be disposed between said enlarged portion of the screw and the tire, substantially as set forth.

In testimony whereof I affix my signature in 25 presence of two witnesses.

HENRY WIDDOWS.
